UNITED STATES PATENT OFFICE.

ROBERT H. AHLERS AND EARL M. POLK, OF DAYTON, OHIO, ASSIGNORS TO THE DAYTON ENGINEERING LABORATORIES COMPANY, OF DAYTON, OHIO, A CORPORATION OF OHIO.

APPARATUS FOR MAKING ARMATURES.

Application filed November 20, 1923. Serial No. 675,970.

To all whom it may concern:

Be it known that we, ROBERT H. AHLERS and EARL M. POLK, citizens of the United States of America, residing at Dayton, county of Montgomery, and State of Ohio, have invented certain new and useful Improvements in Apparatus for Making Armatures, of which the following is a full, clear, and exact description.

10 This invention relates to the manufacture of armatures for dynamo-electric machines, and particularly to the attachment of the armature conductors to the bars of the commutator.

15 One of the objects of the invention is to attach all of the armature conductors to their respective commutator bars simultaneously in order to reduce the cost of manufacture.

20 In order to accomplish this object the risers of the commutator bars each include two spaced deformable portions defining a notch which receives the ends of certain armature conductors. The machine included in the present invention causes the riser portions of the bars to be bent simultaneously against the ends of their respective armature conductors, so as to attach them to their proper commutator bars.

25 Further objects and advantages of the present invention will be apparent from the following description, reference being had to the accompanying drawings, wherein a preferred embodiment of one form of the present invention is clearly shown.

30 In the drawings:

Fig. 1 is an elevation partly in longitudinal section of a machine for forming commutator risers about the ends of armature conductor leads;

Fig. 2 is a plan view thereof;

Fig. 3 is a longitudinal sectional view taken on the line 3—3 of Fig. 2;

Fig. 4 is a view similar to Fig. 3 showing certain parts in other positions;

Fig. 5 is a perspective view of a commutator bar showing its conducting segments and risers;

Fig. 6 is a diagrammatic view on an enlarged scale showing the location of the risers and armature conductor leads before the risers are formed about the leads and also apparatus for performing this operation; and

Fig. 7 is a view similar to Fig. 6 showing

the risers formed about the armature conducting leads.

The process carried out by the machine to be described is illustrated in Figs. 5, 6 and 7. The commutator to be operated upon by this machine includes an annulus of insulated commutator bars. Each bar is represented as a whole by numeral 20 in Fig. 5 and includes a segment 21 wedge-shaped in cross section and two riser bars 22 and 23 having companion deformable portions or tangs 24 and 25, respectively. These bars are maintained in assembled relation by any suitable clamping device which cooperates with a dove tail 26 projecting from each segment and riser bar. The ends 30 and 31 of two armature conductors 32 and 33, respectively, are located between the riser tangs 24 and 25. A plurality of radially movable slides 73 are caused to move radially toward the commutator from a position shown in Fig. 6 to a position shown in Fig. 7 which causes the tangs 24 and 25 to be formed around the commutator bar ends 31 and 30 as shown in Fig. 7. The machine is one which is adapted to receive an armature including a core winding and commutator and which perform simultaneously upon the tangs of the commutator the operations which have just been described.

This machine includes a supporting frame 40 adapted to rest upon a bench 41 which is provided with a hole 42 to permit a bearing 43 carried by the frame 40 to extend below the top of the bench 41. The frame 40 provides a mounting flange 44 to which is attached by bolts 45 and nuts 46 a coupling member or extension 47 which is approximately a hollow cylinder in shape. The coupling 47 includes a mounting flange 48 to which is attached by bolts 49 a cylinder 50 having a removable head 51 attached by screws 52. A piston 53 is mounted for reciprocation in the cylinder 50 and is attached to a piston rod 54. The rod 54 slides through stuffing box 55 provided by the cylinder and is attached by pin 56 through a screw 57. Nuts 58 and 59 cooperate with the screw 57 for a purpose to be described. The upper end of screw 57 is attached by pin 60 to a plunger 61 which slides through the bearing 43 and carries at its upper end a table 62 supporting a plurality of wedge-shaped cams 63. Each

cam includes a cylindrical shank 64 which is threaded to receive a nut 65 by means of which the cam is secured to the table.

The cams 63 are guided by means of a block 70 attached to the frame 40 by screws 71. The block 70 is provided with a plurality of radially extending elongated holes 72 which merge into radially extending notches each for receiving and guiding a slide 73. 10 The slides 73 move along radii from the center of the machine and each slide is provided with an inclined back edge 74 which is engaged by a camming block 63. The inner end or working portion of the slide 73 includes inwardly converging plane surfaces 75 joined by a convex arcuate surface 76, and the plane surfaces 75 merge into concave arcuate surfaces 77. The slide 73 is bored to receive a spring 78 which bears 20 at one end against the block 70 thereby tending to move the slide away from the center of the machine. Upward movement of the slide is prevented by a retaining ring 80 which is attached to the guide block 70 by screws 81.

Centrally thereof, the bearing block carries a detachable bushing 82 having a central aperture 83 for receiving the shaft of an armature.

30 The mode of using the machine is as follows:

The table 62 and the cam block 63 are caused to be located in the position shown in Fig. 4 by introducing fluid pressure into the cylinder 50 below the piston 53 by any suitable means, not shown. Then an armature 90 including a core 91 and a plurality of windings having portions such as shown at 32 and 33 in Fig. 6 and a commutator 35 having bars such as shown in Fig. 5 all assembled on a shaft 92 is placed in the apparatus as shown in Fig. 4, one end of the shaft being received by the bushing 82 in order to locate the armature centrally of the machine. By any suitable means, not shown, the cylinder space under the piston 53 is vented to atmosphere, and fluid pressure is introduced in the cylinder above the piston to cause the table and cam blocks to 40 move in the position shown in Figs. 3 and 2. This operation causes the slides 73 to move from positions indicated in Fig. 6 to positions indicated in Fig. 7. The surfaces 75 and 76 of each slide enter between adjacent tangs 25 and 24 of adjacent commutator bars and cause the companion tangs 24 and 25 of a bar to be pressed against the ends 30 and 31 of the armature conductors while the ends of the tangs are curled over by engagement with the surfaces 77 so that the 45 armature conductors are attached to their respective commutator bars.

By venting the cylinder space above the piston 53 and introducing fluid pressure below the piston, the table 62 is returned to

the position shown in Fig. 4 and the armature can then be removed.

The downward movement of the cams 63 is limited by the nut 59 striking a surface 100 on the coupling 47. The throw of cams 70 63 can be adjusted by regulating the nuts 58 and 59.

While the form of embodiment of the invention as herein disclosed, constitute a preferred form, it is to be understood that other forms might be adopted, all coming within the scope of the claims which follow.

What is claimed is as follows:

1. Apparatus for making an armature including a commutator, the risers of which include spaced deformable portions defining notches for receiving armature conductors which includes in combination, means for holding the armature, a plurality of riser deforming members supported for movement toward the commutator, and means for simultaneously causing said riser deforming members to engage the risers and force them into engagement with their respective conductors.

2. Apparatus for making an armature including a commutator, the risers of which include spaced bendable portions extending transversely from the commutator and defining notches for receiving armature conductors which includes, in combination, means for holding the armature, a plurality of riser bending members supported for movement transversely to the commutator, and means for simultaneously moving said riser bending members against the risers to bend them against their respective conductors.

3. Apparatus for making an armature including a commutator, the risers of which include spaced bendable portions extending substantially radially from the commutator and defining notches for receiving armature conductors which includes, in combination, means for holding the armature, a plurality of forming members each movable between certain risers and adapted to cause the risers of each bar to be bent against certain armature conductors, and means for actuating said members simultaneously.

4. Apparatus for making an armature including a commutator, the risers of which include spaced bendable portions extending substantially radially from the commutator and defining notches for receiving armature conductors which includes, in combination, means for holding the armature, a plurality of forming members each radially movable with respect to the commutator and each adapted to move between certain risers and to bend them against certain armature conductors, a plurality of cams each movable longitudinally of the commutator for moving a forming member, and means for moving all of the cams simultaneously.

5. Apparatus for making an armature including a commutator, the risers of which include spaced bendable portions extending substantially radially from the commutator and defining notches for receiving armature conductors which includes, in combination, 25 a block adapted to support an armature vertically, a plurality of horizontally sliding members supported by the block and each adapted to be received between certain risers and bend them against certain armature conductors, a plurality of cams vertically movable through the block and each adapted to move one of said bending members, a table located below said block and connected with all of the cams, a fluid pressure device 30 located below the table for actuating the table, and a frame for supporting the block, table and fluid pressure means. 35
6. Apparatus for making an armature including a commutator, the risers of which

include spaced bendable portions extending substantially radially from the commutator and defining notches for receiving armature conductors which includes, in combination, 25 a block adapted to support an armature vertically, a plurality of horizontally sliding members supported by the block and each adapted to be received between certain risers and bend them against certain armature conductors, a plurality of cams vertically movable through the block and each adapted to move one of said bending members, a table located below said block and connected with all of the cams, a fluid pressure device 30 located below the table for actuating the table, and a frame for supporting the block, table and fluid pressure means.

In testimony whereof we hereto affix our signatures.

EARL M. POLK.

ROBERT H. AHLERS.
